UNITED STATES PATENT OFFICE

JOHN K. LUTON, OF CLEVELAND, OHIO, ASSIGNOR TO THE CONSOLIDATED IRON-STEEL
MANUFACTURING COMPANY, OF CLEVELAND, OHIO, A CORPORATION OF OHIO

DESIGN FOR A BOILER STAND

Application filed December 18, 1929. Serial No. 33,832. Term of patent 14 years.

To all whom it may concern:

Be it known that I, JOHN K. LUTON, a citizen of the United States, residing at Cleveland, in the county of Cuyahoga and State of Ohio, have invented a new, original, and ornamental Design for Boiler Stand, of which the following is a specification, refer-

ence being had to the accompanying drawing, forming part hereof.

The figure in the drawing is a perspective view of the articles showing my new design.

I claim:

The design for a boiler stand, as shown.
JOHN K. LUTON.
